UNITED STATES PATENT OFFICE.

HENRY L. BORSTELMAN, OF SMALL, IDAHO.

SACK-HOLDER.

1,156,744.

Specification of Letters Patent.

Patented Oct. 12, 1915.

Application filed February 19, 1915. Serial No. 9,364.

To all whom it may concern:

Be it known that I, HENRY L. BORSTELMAN, a subject of the Emperor of Germany, residing at Small, in the county of Fremont and State of Idaho, have invented certain new and useful Improvements in Sack-Holders; and I do hereby declare the following to be a full, clear, and exact description of the invention, such as will enable others skilled in the art to which it appertains to make and use the same.

This invention relates to sack holders and the primary object of the invention is to provide a device for holding the mouth of a sack open to facilitate the filling of the same.

Another object of this invention is to provide a sack holder which has an adjustable spreading arm pivotally connected to a sack supporting bar, and means operable by the pivotal movement of the spreading bar for automatically releasing the sack from engagement with the sack supporting bar.

With the foregoing and other objects in view this invention consists in such novel features of construction, combination and arrangement of parts as will be hereinafter more fully described, illustrated in the accompanying drawings and claimed.

In describing the invention in detail reference will be had to the accompanying drawings wherein like characters designate like or corresponding parts throughout the several views, and in which—

Figure 1 is a top plan view of the improved sack holder, Fig. 2 is a side elevation partially in section of the improved sack holder, showing the same in a sack supporting position in solid lines and in a sack non-supporting position in dotted lines, Fig. 3 is a fragmentary rear view of the sack holder, Fig. 4 is a cross sectional view through the sack holder, Fig. 5 is a sectional view on the line 5—5 of Fig. 3, Fig. 6 is a sectional view on the line 6—6 of Fig. 3, and Fig. 7 is a cross section on the line 7—7 of Fig. 1.

Referring more particularly to the drawings, 1 designates the supporting bar of the improved sack holder, which is substantially rectangular in shape and is provided with key hole slots 2 formed therein, which are provided for receiving hooks, nails or other suitable supporting means indicated at 3 for supporting the sack holder upon a wall or other permanent structure. The bar 1 has a plate 4 secured to the rear surface thereof

substantially equi-distant of its ends, which plate has forwardly extending ears 5 formed upon each end of the lower edge thereof and extending forwardly beneath the lower edge of the bar 1. A plate 6 is pivotally connected to the plate 4 by means of rearwardly extending ears 7 which are formed upon the lower edge thereof, and a pin 8 which extends through the ears 5 and 7 and pivotally connects the two plates 4 and 5. The plate 6 is attached to the forward surface of a bar 9, which bar is hingedly connected, as at 10 to the plate 1. The bar 9 has a sack supporting hook 11 formed on one face thereof and extending forwardly therefrom. A second sack engaging hook 12 is adjustably carried by the bar 9, being formed upon and extending forwardly from a collar 13 which is slidably mounted upon the bar 9 and held in various adjusted positions by means of a set screw 14.

A spiral spring 15 is coiled about the pin 8 and has its opposite ends connected for engagement with the plates 6 and 4 respectively, for holding the plate 1 and the bar 9 in facial engagement with each other. The plate 1 is provided with an opening 16 extending therethrough, in which opening is mounted a catch 17, which has an angularly disposed head 18 formed upon its forward end for engaging the outer surface of the bar 9 for holding it in facial engagement with the plate 1. The catch 17 has a pin 19 extending transversely through its rear end, which pin is seated in a recess 20 formed in the rear face of the plate 1 for pivotally supporting the catch 17. The catch 17 is loosely mounted within the opening 16.

The plate 1 has a spreading arm 25 pivotally connected thereto, which spreading arm is constructed of a flat metal bar and has its rear end twisted and rolled upon itself, as is shown at 26. The twisted and rolled end 26 of the bar 25 is inserted through an opening 27 formed near the upper edge of the plate 1 and substantially equi-distant of the ends of the same, for pivotally connecting the spreading arm to the supporting plate 1.

The spreader arm 25 is composed of three lengths or bars or metal, 28, 29 and 30, which bars are adjustably connected to each other, by means of slots 32 formed therein, in which slots are slidably seated bolts 33. The sections 30 and 29 are adjustably held in connection with each other by means of a

spiral spring 34, which is coiled about the engaging section of the bars and has its end in engagement with lugs 35 and 36, which are formed upon the bars 29 and 30 respectively, as is clearly shown in Figs. 1 and 2 of the drawings.

The bar 30 has a guideway 37 formed in its outer end, in which guideway is seated a sack engaging bar 38. A tong 39 projects 10 longitudinally from the end of the bar 30 and extends through the sack engaging bar 38 for holding the bar against movement independently of the bar 30. The bar 38 is 15 arcuate in shape, and has points 40 formed upon the upper edges of its outer ends for engagement with the upper edge of a sack for holding the sack open.

A bracing bar 41 is connected to the spreading arm 25 and extends downwardly 20 therefrom and rearwardly toward the plate 1. A reinforcing bar 42 is secured to the arm 25 and the bar 41.

A wire 44 has one of its ends secured to the plate 1, as at 45, and it is bent to form 25 resilient convolutions 46, from one end of which convolutions a wire extends upwardly and downwardly, forming a substantially U-shaped section 47, which engages the under surface of the arm 25. The downwardly 30 projecting arm 48 of the U-shaped section 47 of the wire 44 is coiled to form a plurality of resilient spring action convolutions 49. The end 50 of the wire 44, opposite to the end which is attached to the plates 1 and 45, 35 extends through the plate and has a head 51 formed thereupon, the purpose of which will be hereinafter more fully described.

In the operation of the improved sack holder: The plate 1 is supported by a permanent support or wall indicated at 60, by the insertion of the hooks or nails 3 into and through the openings 2. After the plate 1 has been properly attached to the permanent support, one section of the upper edge of a 45 sack is attached to the hooks 11 and 12, after which the spreading arm 25 is moved into a substantially horizontal position, as is illustrated in solid lines in Fig. 2 of the drawings. When the spreader arm 25 is moved 50 into a horizontal position, it forces the U-shaped section 47 of the wire 44 downwardly against the spring action of the resilient convolutions 46 and 49, and it is held in a downward or horizontal position by attaching 55 the hook 51 to the arm or length 48 of the wire 44. The sack engaging bar 38 is then positioned within the mouth of the sack and a section of the upper marginal edge of the sack is engaged by the upstanding point 40, which holds the sack in an 60 open position for permitting of the filling of the same. After the sack has been filled the section 51 is moved out of engagement with the projection 48, which allows the 65 resilient convolutions 46 and 49 to act, forcing

the bar or arm 25 upwardly into the position indicated in dotted lines in Fig. 2 of the drawings. When the sack is being filled, the bar 9 is held in engagement with the plate 1 by means of the catch 17. When the arm 25 is moved upwardly by the action of the resilient spring convolutions 46 and 49, the end of the same which is secured to the plate 1 will strike the end of the catch 17, moving it out of engagement with the plate 9. When the catch 17 is moved out of engagement with the plate 9, the weight of the sack will force the bar 9 downwardly and outwardly from the plate 1 and permit the sack to slip from the hooks 11 and 12.

From the foregoing description taken in connection with the accompanying drawings the advantages of construction and of the method of operation of the improved sack holder will be readily apparent to those skilled in the art to which this invention appertains and, while in the foregoing description, the principle of the operation of this invention has been described together with various features of construction, it is to be understood that certain minor features of construction, combination and arrangement of parts may be altered to suit practical conditions provided such alterations are comprehended within the scope of what is claimed.

What is claimed is:—

1. In a sack holder, an attaching plate, a bar pivotally connected to the lower edge of said attaching plate, means for normally holding said bar in facial engagement with said attaching plate, a sack engaging hook formed integrally with one end of said pivoted bar, a collar slidably mounted upon the end of said bar remote from said sack engaging hook, means for holding said collar in various adjusted positions, and a sack engaging hook formed upon said collar.

2. In a sack holder, an attaching plate, a bar pivotally connected to said plate, a sack engaging hook formed integrally with said bar at one end of the same, a collar slidably mounted upon said bar remote from said hook, means for holding said collar in adjusted position, a sack engaging hook formed upon said collar, a catch pivotally connected to said attaching plate and provided for engaging the upper edge of said pivoted plate for holding said pivoted plate in facial engagement with said attaching plate, and a spring operatively connected to said plate for automatically moving said pivoted plate into facial engagement with said attaching plate after movement therefrom.

3. In a sack holder, a supporting plate, sack engaging means carried by said plate, a spreader arm pivotally carried by said plate and extending outwardly therefrom for engagement with a section of a sack

for holding the same open, means carried by said plate and engaging said spreader arm for automatically forcing said spreader arm out of a sack engaging position, means carried by said plate and engaging said sack 5 engaging means for holding it in a sack supporting position, said means automatically operable by the movement of said spreader arm out of a sack engaging position, for releasing said sack engaging means.

4. In a sack holder, an attaching plate, a bar pivotally carried by said plate, means for normally holding said bar in facial engagement with said attaching plate, sack 15 engaging hooks carried by said bar, and means for holding said bar in facial engagement with said plate.

5. In a sack holder, an attaching plate, a bar pivotally carried by said plate, means for normally holding said bar in facial engagement with said attaching plate, said engaging hooks carried by said bar, means for holding said bar in facial engagement with sack plate, a spreader arm pivotally connected to said attaching plate and composed of a plurality of adjustably connected sections, a sack engaging bar carried by the outer end of said spreader arm, means carried by said plate for automatically moving said spreader arm out of a sack 25 engaging position, and means for holding said spreader arm in a sack engaging position.

30

ing position, and means for holding said spreader arm in a sack engaging position.

6. In a sack holder, an attaching plate, a bar pivotally connected to said plate, means for normally holding said bar in facial engagement with said attaching plate, a sack 35 engaging hook formed integrally with said bar upon one end of the same, a collar slidably carried by said bar remote from said sack engaging hook, means for holding said collar in adjusted positions upon said bar, a sack engaging hook formed upon said collar, means for holding said bar in facial engagement with said plate, a spreader arm pivotally connected to said attaching plate 40 and composed of a plurality of adjustably connected sections, a sack engaging bar carried by the outer end of said spreader arm, and means carried by said plate for automatically moving said spreader arm out of 45 a sack engaging position, and means for holding said spreader arm in a sack engaging position.

In testimony whereof I affix my signature in presence of two witnesses.

HENRY L. BORSTELMAN.
